(57) **CLAIM**

I claim the ornamental design for a ring with Maltese cross,
as shown.

DESCRIPTION

FIG. 1 is a perspective view of the Maltese cross ring of the
present invention showing the ornamental aspects thereof;

FIG. 2 is a front elevation view of the ring of FIG. 1;

FIG. 3 is a top plan view of the ring of FIG. 1, it being
understood that the bottom plan view is identical; and,

FIG. 4 is a rear elevation view of the ring of FIG. 1.
